UNITED STATES PATENT OFFICE.

HENRY VAN DEWATER, OF WORCESTER, MASSACHUSETTS.

IMPROVEMENT IN WATER-WHEELS.

Specification forming part of Letters Patent No. 38,775, dated June 2, 1863.

To all whom it may concern:

Be it known that I, HENRY VAN DEWATER, of Worcester, in the county of Worcester and State of Massachusetts, have invented a new and Improved Water-Wheel; and I do hereby declare that the following is a full, clear, and exact description of the same, reference being had to the accompanying drawings, making a part of this specification, in which—

Figure 1 is a vertical section of my invention, taken in the line $x x$, Fig. 2. Fig. 2 is a plan or top view of the same, the top of the wheel-case being removed; Fig. 3, a detached inverted plan of the wheel; Figs. 4 and 5, detached views of a bucket belonging to the wheel.

Similar letters of reference indicate corresponding parts in the several figures.

This invention relates to an improved water-wheel of that class which are placed on vertical shafts, are inclosed within a case, and have a draft-tube connected with the case.

The invention consists in a peculiar construction of the wheel, and also in a novel construction and arrangement of the case and water-chamber in which the shaft of the wheel is stepped, whereby it is believed that a very simple and efficient water-wheel of the kind specified is obtained.

To enable those skilled in the art to fully understand and construct my invention, I will proceed to describe it.

A represents a case or penstock, in the bottom of which a circular opening is made to receive a tube, B, which is a trifle larger in diameter than the water-wheel, and which is commonly termed a "draft-tube."

C represents a case of cylindrical form which incloses the water-wheel. The upper part, a , of this case is rather larger in diameter than the lower part, b , so as to form a ledge or shoulder, c , which rests on the edge of the opening in the bottom of the penstock, the part a of the case being within the penstock, and the part b within the upper part of the draft-tube B, as shown in Fig. 1. The upper part, a , of the case C is provided with four chutes, D', the sides d of which are of curved form, as shown in Fig. 2. The lower part, b , of the case C is of flaring form, so that its lower edge will fit snugly against the inner side of the draft-tube B, as shown at e in Fig. 1.

D represents the wheel, the shaft E of which is stepped on an upright, f , in an inverted conical chamber, F, which rests on cross-pieces g in the draft-tube. The wheel D has a peculiar-shaped hub, G, the lower part, h , of which is of cylindrical form, the upper part, i , being inclined at an angle of about forty-five degrees, as shown clearly in Fig. 1. The surfaces of the two parts $h i$ have about an equal area, and at the upper edge of the part i of the hub there is a horizontal rim or flange, j .

H represents the buckets which are attached to the parts $h i$ of the hub G. These buckets are of concave form at their face sides, as shown clearly in Fig. 4, and they are provided with a lip, k , at their outer edge, which projects forward and render the buckets somewhat of cup or dish form to catch and retain the water. The upper edges of the buckets are beveled or of miter form, corresponding with the inclined surface i of the hub G, and the several buckets lap over each other in an inclined position, spaces of suitable capacity being allowed between the lower ends of the buckets to form issues. Each bucket H has a flange, I, connected with it, which is the segment of a rim, l , the several segments being in contact, so as to form a continuous band all around the wheel when the buckets are attached to it. (See Fig. 1.) To the underside of the rim or flange j there are attached a series of pendent lips, m , one in line with each bucket and having a slight angular position relatively with them. These pendent lips m do not project down a great distance, as they are designed simply to form prominences for the water to catch or act against as it enters the buckets, thereby serving as guides. The hub G has a hole, n , made in it to allow the inverted conical chamber F to fill with water.

The advantages of the invention are as follows: The water is made to act in the most efficient manner upon the wheel. The hub G, in consequence of being formed of a vertical cylindrical part, h , and inclined part i , gives the buckets H a great capacity at their outer parts, so that they will freely receive the water, while the lips m properly direct the water into the buckets, and the lips k serve to catch or retain it. These are essential features pertaining to the wheel and render it capable of working in the most favorable manner under the per-

sive force of the water, the power of the water due to gravity being obtained as the water escapes down through the issues. The chamber F keeps the step of the shaft perfectly lubricated, and at the same time the upward pressure of the water in F against the under side of the hub G takes the weight of the wheel off from the step, while the chamber F in consequence of its inverted conical form causes an equal draft or suction all around the bottom of the wheel. The lower end of the draft-tube B is immersed in water, so as to cause the usual suction or draft, as in the French Jouval wheel.

Having thus described my invention, what I claim as new, and desire to secure by Letters Patent, is—

1. The buckets H, constructed as shown, so as to conform to the shape of the hub G, and

provided with the lips k and segment-flanges I, as and for the purpose set forth.

2. The pendent lips m, attached to the under side of the rim l of the hub G, when arranged relatively with the buckets H, to operate as and for the purpose herein set forth.

3. The combination of the hub G, buckets H, provided with the lips k, and flanges I, the pendent lips m, and case C, provided with the chutes D', all arranged to operate as and for the purpose herein set forth.

4. The inverted conical chamber F, placed below or underneath the wheel D, and inclosing the step of the shaft E, as and for the purpose herein set forth.

HENRY VAN DEWATER.
